DESIGN FOR A SPEAKER HOUSING

Benjamin W. Lowell, Jr., Richmond Heights, Mo.

Application December 29, 1945, Serial No. 125,211

Term of patent 14 years

(Cl. D26—14)

To all whom it may concern:

Be it known that I, Benjamin W. Lowell, Jr., a citizen of the United States, residing in the city of Richmond Heights, in the county of St. Louis and State of Missouri, have invented a new, original, and ornamental Design for Speaker Housings, of which the following is a specification, reference being had to the accompanying drawing, forming part thereof.

Fig. 1 is a side elevational view of a speaker housing showing my new design.

Fig. 2 is a bottom plan view.

I claim:

The ornamental design for a speaker housing, substantially as shown.

BENJAMIN W. LOWELL, JR.
